UNITED STATES PATENT OFFICE

ARCHIBALD STURROCK, OF VICTORIA, BRITISH COLUMBIA, CANADA

LOGGING CAR

Application filed April 1, 1931. Serial No. 526,941.

My present invention relates to railway cars for transporting logs and it has for an object to provide certain new and useful appliances which will enable the use of the present well known Simplex bolster along with the arch bar truck in logging car structure.

Further, the invention has for its object to provide an outside friction which may be applied to the bolster without changing the construction thereof and which will not interfere with the proper functioning of either the bolster, the truck or the cushioning springs.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:—

Figure 1 is a side elevation of a portion of a logging car with my invention, the truck being indicated in dotted lines.

Figure 2 is an enlarged plan view of one-half of the portion of the logging car shown in Figure 1, the truck frame, etc., being omitted.

Figure 3 is a vertical cross section on the line 3—3 of Figure 2.

Figure 4 is a detail side elevation of the outer friction casting per se.

Figure 5 is a detail elevation of the casting taken at right angles to Figure 4.

Figure 6 is a detail inverted plan of the casting shown in Figure 4.

In the drawings, in which like numerals of reference indicate like parts in all of the figures, 1 represents the truck or lower bolster, 2 the truck center plate and 3 the body center plate. The truck bolster 1 is formed of an inverted U channel beam, the top surface of which inclines downwardly, as at 4, and outwardly from the center to a point beneath the arch bar 43 of the truck side frame, from whence it inclines upwardly to the end of the beam as at 5.

The strengthening iron is indicated by 6 and this iron is secured at the center 7 and has its ends turned over the ends of the bolster beam to which it is securely riveted as at 9, there being filler members 10 provided for the usual purpose. The construction of the truck bolster is that of the well known Simplex bolster and per se is not of my invention.

Secured to the outer ends of the bolster are outside frictions, each of which comprises a casting consisting of a base part 11 from which depend an inside flange 12, an outside flange 13, and front and back flange plates 14, the latter having riveting holes 15 hereinafter again referred to.

16 is the rubbing head of the outer friction, which head is connected to the base part 11 by suitable webs 17 and 18.

It will be noted that the several flanges 12, 13 and 14 cooperate with the base 11 to form a cup-like structure within which is located a curved saddle 19, the purpose of which is to rest on the curved upper surface of the end 8 of the strengthening iron. The depth of the inner flange 12 is such that when the outer friction is in position on the bolster it may be welded as at 20 to the surface 5 of the bolster and the outer flange 13 is of a length to extend over or overlie the extreme end of the bolster, thus enclosing the turned-over end 8 of the strengthening iron and also enclosing the filler block 10.

In mounting the outer friction on the projecting end of the truck bolster the outer rivet which secures the sheathing 44 that has the truck frame guideways, to the bolster is removed. This rivet is replaced by a new one 45 which also passes through the apertures 15 and serves to secure the flange plates 14 to the sides of the bolster.

21 designates the longitudinal body beams (usually of wood) of the car, these beams being secured together side by side by suitable bolts 46, which also serve to secure the bolster mounting plates 22 in place.

The body center plate 3 is secured to the beams 21 by suitable bolts 23 as shown.

The body bolster consists of laterally projecting L-irons 24, to the inner ends of which are riveted angle irons 25, the latter being

also securely riveted to the adjacent plate 22. The L-irons 24 of each bolster are spaced apart by U-shaped irons 26 and 27 riveted to the bolster irons 24, one of the U-shaped brace irons 26 being located above the location of the inner friction and the other 27 being located above the location of the outer friction.

28 designates the outer friction rubbing block which is mounted on the body bolster 10 by means of angle irons 30 riveted at 32 to the irons 24 and riveted at 31 to the ears of the rubbing block, a suitable shim 29 being interposed if necessary for proper spacing.

33 designates the log bunker which has 15 flanges 34 to rest on the irons 24 to which they are riveted or otherwise secured as at 35.

36 is the inner friction casting whose base 37 is riveted at 38 to the truck bolster 1. The inner friction 36 has its friction head connected to the base 37 by suitable webs 39.

The inner friction block 30 may be of the same construction as the friction block 28 and it may be secured to the body bolster in a similar manner as by the use of angles 41 25 riveted to the block 40 and to the bolster irons 24.

42 designates the truck side frame, the arch bar 43 of which overlies the truck bolster at about the lowest point of the dip of the upper 30 face thereof and the side frame 42 is thus located in a plane between the inner and outer frictions. The inner friction may be dispensed with if desired.

From the foregoing description, taken in 35 connection with the accompanying drawings, it is thought the complete construction, operation and advantages of my invention will be clear to those skilled in the art to which it relates.

40 What I claim is:

1. In logging cars, in combination with a truck bolster and an arched bar truck side frame through which the end of said bolster projects, said bolster including a channel iron 45 and a strengthening iron, the ends of which strengthening iron are curved around the ends of the channel iron and are secured thereto; of an outer friction comprising a body member having inner and outer flanges spaced apart and having front and back 50 flange plates spaced apart to straddle a projecting end of said bolster, said friction also including a rubbing head united to said body member by connecting webs, and means 55 securing said friction in place.

2. In logging cars, in combination with a truck bolster and an arched bar truck side frame through which the end of said bolster projects, said bolster including a channel iron 60 and a strengthening iron, the ends of which strengthening iron are curved around the ends of the channel iron and are secured thereto; of an outer friction comprising a body member having inner and outer flanges spaced apart and having front and back 65

flange plates spaced apart to straddle a projecting end of said bolster, said friction also including a rubbing head united to said body member by connecting webs, said friction also including a saddle portion to set on the curved-around end portion of said strengthening iron, and means securing said friction in place.

3. In logging cars, in combination with a truck bolster and an arched bar truck side 75 frame through which the end of said bolster projects, said bolster including a channel iron and a strengthening iron, the ends of which strengthening iron are curved around the ends of the channel iron and are secured 80 thereto; of an outer friction comprising a body member having inner and outer flanges spaced apart and having front and back flange plates spaced apart to straddle a projecting end of said bolster, said friction also 85 including a rubbing head united to said body member by connecting webs, said inner flange being welded to the top face of said channel iron and said outer flange in part overlying the end face of said channel iron.

4. In logging trucks, a body bolster and a truck bolster, the latter including a channel beam and a strengthening iron whose ends are curved over and around the outer end of the channel beam and secured thereto, and arched bar truck frames through which the ends of said truck bolsters project; combined with inner frictions and rubbing irons secured to said truck bolster and to said body bolster respectively in positions to the inner 100 side of the position of the arched bars of said truck frames, and outer frictions and rubbing irons secured to said truck and body bolsters respectively and located to the outer sides of the positions of the arched bars of 105 said truck frames, said outer friction overlying the curved over end of said strengthening iron and embracing the same.

5. As a new article of manufacture, an outer friction for logging truck bolsters 110 which comprises a base member consisting of a horizontal base plate from the margins of which depend an inner flange and an outer flange and front and back flange plates forming a cup-like structure shaped to fit over the end of a truck bolster of the channel beam type, which bolster has a strengthening iron whose ends are curved over the ends of the beam and secured thereto, said base member including a saddle located within the cup-like structure to rest on a curved-over end of the strengthening iron, said friction also including a friction head carried by said base member and located above the same.

6. As a new article of manufacture, an 125 outer friction for logging truck bolsters which comprises a base member consisting of a horizontal base plate from the margins of which depend an inner flange and an outer flange and front and back flange plates form-

ing a cup-like structure shaped to fit over the end of a truck bolster of the channel beam type, which bolster has a strengthening iron whose ends are curved over the ends of the beam and secured thereto, said base member including a saddle located within the cup-like structure to rest on a curved-over end of the strengthening iron, said friction also including a friction head carried by said base member and located above the same, said front and back flange plates having apertures and being positioned to overlie the sides of the channel beam of the truck bolster.

7. As a new article of manufacture, an outer friction for logging truck bolsters which comprises a base member consisting of a horizontal base plate from the margins of which depend an inner flange and an outer flange and front and back flange plates forming a cup-like structure shaped to fit over the end of a truck bolster of the channel beam type, which bolster has a strengthening iron whose ends are curved over the ends of the beam and secured thereto, said base member including a saddle located within the cup-like structure to rest on a curved-over end of the strengthening iron, said friction also including a friction head carried by said base member and located above the same, said front and back flange plates having apertures and being positioned to overlie the sides of the channel beam of the truck bolster, the inner flange of said friction being of a depth to be secured to the top of the channel beam, and the outer flange being of a depth to overlie the end of the channel beam.
